Primary Examiner — Samantha Wood*Assistant Examiner* — Emily A Caven(74) *Attorney, Agent, or Firm* — GLOBAL IP COUNSELORS, LLP(57) **CLAIM**

The ornamental design for a pet toy, as shown and described.

DESCRIPTION

FIG. 1 is a top perspective view of a pet toy in accordance with our new design;

FIG. 2 is a bottom perspective view thereof;

FIG. 3 is a top view thereof;

FIG. 4 is a bottom view thereof;

FIG. 5 is a first side view thereof;

FIG. 6 is second side view thereof;

FIG. 7 is a front view thereof; and,

FIG. 8 is a back view thereof.

The broken lines in the drawings illustrate portions of the pet toy that form no part of the claimed design.

1 Claim, 4 Drawing Sheets(56)
